(57) **CLAIM**

The ornamental design for a urinal screen, as shown and described.

DESCRIPTION

FIG. 1 is a front, left, and top side perspective view of a first embodiment of a urinal screen embodying our new design; FIG. 2 is a top plan view thereof; FIG. 3 is a bottom plan view thereof; FIG. 4 is a right side elevational view thereof; FIG. 5 is a left side elevational view thereof; FIG. 6 is a front side elevational view thereof; FIG. 7 is a back side elevational view thereof; FIG. 8 is a front, left, and top side perspective view of a second embodiment of a urinal screen embodying our new design;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front side elevational view thereof; and,

FIG. 14 is a back side elevational view thereof.

The evenly dashed broken lines are used to illustrate features of the urinal screen which form no part of the claimed design. The dash-dot-dash broken lines illustrate the boundary of the claimed invention and form no part of the claimed design.
